UNITED STATES PATENT OFFICE.

RICHARD C. LEAKE, OF ROCHESTER, NEW YORK, ASSIGNOR TO GENERAL RAILWAY SIGNAL COMPANY, OF ROCHESTER, NEW YORK, A CORPORATION OF NEW YORK.

STARTING SWITCH FOR SINGLE-PHASE MOTORS.

Application filed June 7, 1920. Serial No. 387,127.

To all whom it may concern:

Be it known that I, RICHARD C. LEAKE, citizen of the United States, residing at Rochester, in the county of Monroe and State of New York, have invented certain new and useful Improvements in Starting Switches for Single-Phase Motors, of which the following is a specification.

This invention relates to centrifugal switches, and more particularly to a switch for starting single phase induction motors.

The principal objects of my invention are to devise a speed-responsive switch which will act positively to break and make the desired circuit connections at predetermined speeds, which will break contact quickly and spread the arc over a comparatively large surface, thereby avoiding injury of the contacts, and which will possess the various other features of construction and operation desirable in switches of this type. My improved switch is also arranged and constructed so as to act as a fan and blow air through the motor for ventilating and cooling it, thereby avoiding the expense and complication of an extra fan for this purpose.

Other specific features and advantages will appear hereinafter as the description progresses.

In describing the invention in detail reference will be made to the accompanying drawings in which:—

Figure 1 is a diametrical section through a conventional single phase motor showing my improved starting switch applied thereto;

Fig. 2 is a transverse section through the motor and switch on the line 2—2 in Fig. 1;

Fig. 3 is a fragmentary inside view of the end cap of the motor and shows the arrangement of contact posts;

Fig. 4 is a view similar to Fig. 3 showing a modified construction of the stationary contact blocks;

Fig. 5 is a diametrical section on a line 5—5 in Fig. 4; and

Fig. 6 shows the switch diagrammatically in perspective, with parts broken away and spread apart, together with the circuit connections preferably employed with the switch.

Referring to the accompanying drawings, I have shown my improved centrifugal

switch applied to a single phase motor of conventional construction comprising a frame F, a laminated stator S with coils or windings W constituting the usual starting and running windings for the stator, and a rotor R fixed to a shaft 1, which is journaled in bushings 2 pressed in bearing housings 3 integral with the end caps C of the motor. These end caps C are provided with ventilating openings 4 (see Fig. 3) which are covered by a splash cover or shield D. In the shield D is a hole lined with an insulating bushing 5 for receiving the power wires. The end cap C and shield D are fastened to the frame F by nuts 6 on threaded rods 7 extending through the motor.

Secured to the end caps C are three insulated contact posts 8^a, 8^b, 8^c, (see Figs. 1 and 3) which are arranged at substantially equal intervals around the shaft 1. Each of these contact posts comprises a block 9, preferably made of German silver or similar material, and a stem 10 which has a flared head countersunk in said block and which is fastened to the end cap C but insulated therefrom. The stem 10 extends through a bushing 11 and washers 12 of insulated material, and is provided with a nut 13 for clamping the stem to the end cap C. Two of the posts 8^a and 8^b have additional nuts 85 for attaching wires. An extra binding post 15, supported and insulated in a similar manner, but having no contact block is also secured to the end cap C to provide attachment for other wires leading to the stator winding, these wires being taken through an insulated bushing in the end cap C.

Cooperating with the three contact posts 8^a to 8^c is a contact ring 16, preferably made of phosphor bronze, steel or a similar comparatively hard conducting material. This ring 16 is fastened by tubular rivets 17 to a disk 18 of insulating material fitting loosely on the shaft 1, each of these rivets also passing through a spacer 19 and a ring 20, both of insulating material. A sleeve 21 on the shaft 1 is provided with a flange 21^a having a loose slip fit with the circular groove formed between the disk 18 and the ring 20. Fas- 100 tened to the sleeve 21 is a circular member 22 having radially extending arms 23 with curved ends. In the construction illustrated 105 there are three of these arms 23 arranged

120° apart around the shaft 1, as shown in Fig. 2. Fastened to the rotor R by screws 24, is a plate 25 which is formed with three pairs of ears or projections 26 arranged 120° apart and straddling the arms 23. These projections 26 are shaped as shown in Fig. 1 and constitute in effect fan blades.

Associated with each pair of the projections 26 is one of the centrifugal elements 10 of the switch. This element comprises a weight in the form of a roller 27 loosely journaled on a pin 28 carried by the lower ends of a pair of links 29, which are pivotally supported at their upper ends on a pin 15 30 fastened to the projections 26. A collar 31 is fastened to the plate 25 and constitutes a guiding support for the inner end of the sleeve 21. Another collar 32, having a sliding fit on the shaft 1, guides the outer 20 end of the sleeve 21; and between these collars 31 and 32 is a compression spring 33 surrounding said shaft.

Operation.—When the rotor and shaft 1 are at rest, the parts are in the position 25 shown, the rollers 27 being in their inner position, and the contact ring 16 being pressed by the spring 33 against the blocks 9 of the contact posts 8^a—8^c. These contact posts form a three-point support for 30 the contact ring 16, thereby assuring intimate contact with each block 9. When the motor is started and the shaft 1 revolves, the contact ring 16 is held stationary by its drag on the contact posts, the disk 18 and 35 ring 20 slipping on the flange 21^a of the sleeve 21. As the speed of the shaft 1 increases the rollers 27 are thrown out by centrifugal force into contact with the arms 23, and at a predetermined speed, the pressure exerted by these rollers against these 40 arms overcomes the tension of the spring 33 and slides the sleeve 21 axially on the shaft 1, the outer movement of said rollers being limited by the curved ends of the arms 23. As the sleeve 21 is shifted, the contact 45 ring 16 is pulled away from the contact blocks 9, thereby breaking the circuit through the starting winding. As soon as the contact ring 16 leaves the blocks 9, it 50 accelerates, and all of the parts revolve together with the shaft 1, without any engagement or rubbing between stationary and moving parts. If the speed of the motor falls below a critical speed, the spring 33 55 overcomes the centrifugal force exerted by the rollers 27 and returns the parts to the position shown, thereby again cutting in the starting winding. The projections 26 act as fan blades and draw the air in through 60 the usual ventilating holes in the rotor and propel it by the ventilating openings 4 in the end cap C. This constitutes one of the important features of the invention since it obviates the expense and complication of 65 a special ventilating fan.

Referring to Fig. 6, 35 designates the running winding, and 36 the starting winding. When the switch 37 is closed, the running winding 35 is connected directly across the supply conductors 38, and the starting winding 36 is connected in multiple therewith 70 between the contact posts 8^a and 8^b. The contact post 8^c is a dead post which is used with the other two so as to bear against the contact plate 16 at three points. 75

One important feature of my invention, is the quick action of the switch. It will be noted that when the rollers 27 move the arms 23, the angle of the links 29 changes, and this increases the component of the centrifugal force parallel with the shaft 1 and acting 80 on the arms 23, and also that the radius of rotation of the rollers 27 also increases at the same time. As a result, when the rollers 27 overcome the tension of the spring 85 33 and start their outward movement, they fly out quickly, because they have an increased mechanical advantage over the spring 33 as they move out, and also acquire an increased speed and consequently an increased 90 centrifugal force. This quick movement of the contact ring 16, similar to the operation of a snap switch, prevents burning or injury of the contacts by long drawn out arcs. Also, as soon as the pressure of 95 the contact ring 16 on the blocks 9 is relaxed, this ring commences to rotate so that any arc that may be drawn is spread over a comparatively wide surface, thereby obviating local heating and pitting. It is found 100 in practice that minute projections are sometimes drawn up on the contacts by the arcing, but these projections are rubbed down when the motor slows down and stops, so that the contact ring and blocks maintain a 105 serviceable surface after a large number of operations.

While considerable wear of the contacts may take place, both on the ring 16 and the blocks 9, without materially altering the 110 critical speed at which the switch will open, such wear may be reduced, if desired, by increasing the area of the stationary contacts 9. Such an arrangement is shown in Figs. 4 and 5, in which two segmental contact 115 blocks 40 and 40^a are secured to the end cap C by stems 41 which pass through insulating bushings 42 and washers 43 and are clamped to the end plate C by nuts 44 in much the same way as in the construction 120 described. A circular ridge or boss is formed on the end cap C, and a piece of insulation 45 is inserted between each contact piece and this boss, so as to prevent turning or twisting of the contact piece and yet 125 maintain it insulated from the motor frame. In this modified construction the shape of the ventilating openings 4 is changed.

The specific constructions shown and described are merely illustrative of the inven- 130

tion and are susceptible of adaptation and modification in practice without departing from the invention.

What I claim as new and desire to secure by Letters Patent of the United States is:—

1. In a centrifugal switch, the combination with a shaft, of a sleeve movable axially on the shaft and biased in one direction, centrifugal members carried by pivoted levers 10 connected to the shaft and acting to move the sleeve in the other direction, said members in moving outward increasing the component of their centrifugal force acting on the sleeve, and circuit controlling means actuated by said sleeve.

2. In a centrifugal switch, the combination with a shaft, of a sleeve movable axially on the shaft and having radial arms, a member rotating with the shaft and having pairs 20 of projections straddling the said arms, centrifugal members pivotally supported by links from said projections and arranged to bear against the corresponding arms, a spring biasing the sleeve in one direction, and circuit controlling means actuated by 25 the sleeve.

3. A centrifugal switch for starting single phase induction motors comprising a plurality of insulated contact posts secured to 30 an end plate of the motor, an insulated contact ring movable axially on the motor shaft, a spring acting to press said ring against the contact posts, and speed-responsive means comprising a roller carried by a lever 35 for moving the ring in opposition to said spring, and a support for said lever attached

to the end of the rotor and having a plurality of radially extending flat projections adapted to act as fan blades.

4. A centrifugal switch comprising, in 40 combination with a shaft, a contact ring movable axially on the shaft, insulated stationary contacts cooperating with said ring, pivoted rollers carried by movable levers for actuating said ring into engagement 45 with said stationary contacts, and supports for said levers formed with radial projections acting as fan blades.

5. In a centrifugal switch, the combination with a shaft, of a sleeve movable axially on the shaft and biased in one direction, a centrifugal device including members carried by the shaft and acting to move the sleeve in the other direction, said members in moving outward increasing the component 50 of the force produced by said centrifugal device upon the sleeve, and circuit controlling means actuated by said sleeve.

6. In a centrifugal switch, the combination with a shaft, of a sleeve movable axially on the shaft and biased in one direction, a centrifugal device comprising swingingly supported heavy rollers acting to move the sleeve in the other direction, said rollers in moving outward transmitting an increasing component of their centrifugal force upon the sleeve, and circuit controlling means actuated by said sleeve.

In testimony whereof I have affixed my signature.

RICHARD C. LEAKE.
